[57] **CLAIM**

The ornamental design for a dual purpose microphone supporter, as shown and described.

DESCRIPTION

FIG. 1 is a perspective view of a dual purpose microphone supporter showing my new design, with the environmental microphone and user shown in broken lines;

FIG. 2 is a perspective view of the supporter shown as resting on a horizontal surface with an environmental microphone in broken lines;

FIG. 3 is a left side elevational view thereof;

FIG. 4 is a front elevational view thereof;

FIG. 5 is right side elevational view thereof;

FIG. 6 is a bottom plane view; and

FIG. 7 is a top plane view.

FIG. 1

FIG. 2

FIG. 3

FIG. 4

FIG. 5
